UNITED STATES PATENT OFFICE.

ELMER MC GUIRE, OF DAYTON, OHIO.

SUSPENDERS.

SPECIFICATION forming part of Letters Patent No. 740,584, dated October 6, 1903.

Application filed June 27, 1903. Serial No. 163,814. (No model.)

To all whom it may concern:

Be it known that I, ELMER MC GUIRE, a citizen of the United States, residing at Dayton, in the county of Montgomery and State of Ohio, have invented certain new and useful improvements in Suspenders; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to new and useful improvements in suspenders for supporting trousers.

The object of the invention is to combine with a pair of suspenders an additional strap which is attachable at one end to a button immediately above the hip-pocket in the trousers and is designed to support the trousers at that point.

The improvement is especially adapted for policemen, detectives, and other officers of the law who habitually carry the smaller firearms in the hip-pocket. The weight upon the trousers at that point is not met by the usual suspenders, owing to the fact that the position of the hip-pocket is on one side of the button-straps in the rear.

Preceding a detail description of my invention reference is made to the accompanying drawings, of which—

Figure 1 is a rear view of a figure with my improved suspenders shown in position. Fig. 2 is a view of the same removed from the person. Fig. 3 is a view of a portion of the suspenders, showing an adjustable connection between the hip-pocket strap and one of the shoulder-straps of the suspenders.

In a detail description of the invention similar reference characters indicate corresponding parts.

1 and 2 designate the shoulder-straps of the usual suspenders, the rearward ends of which terminate in button-eyelets 7 and the forward

ends of which terminate in front button-straps 8. This description comprises the usual shoulder-strap suspenders, and the features comprising the present invention will now be described.

3 designates a hip-pocket strap which is attachable to one of the shoulder-straps of the suspenders at 9, as shown in Fig. 1. The point of attachment of the hip-pocket strap 3 with the suspender-strap would in this case be in the rear of the shoulder of the wearer, or the attachment of the said hip-pocket strap 3 may be at a point 4, as shown in Fig. 2, which would be in front of the shoulder of the wearer when the suspenders are in position on the body, as in Fig. 1. The point of attachment of the end of the hip-pocket strap 3 may also be adjustable, as shown in Fig. 3, by means of a slide or buckle 6. The strap 3, as shown in Figs. 1 and 2, has a permanent attachment at either 9 or 4 with the shoulder-strap 2, or the attachment, as before stated, may be adjustable by means of a suitable slide or buckle 6. The lower end of the strap 9 has an eyelet-piece 10, which receives a button 5, secured to the waistband of the trousers immediately above the hip-pocket 11. It will therefore be seen that the weight upon the trousers due to the revolver or firearm carried therein is in a line with the lower attached end of the hip-pocket strap 3, and as a consequence such weight will be borne from the shoulder of the wearer and much discomfort and inconvenience will be avoided.

I am aware that various devices have been provided in suspenders, and consist in the nature of regulating-straps or equalizers to more equally support the trousers. Therefore I do not claim, broadly, such arrangements; but what I do claim is a specially-constructed hip-pocket strap connected with one of the shoulder-straps of a pair of suspenders and also connecting with a button upon the trousers immediately above and in line with the hip-pocket.

Having described my invention, I claim—
In a suspender for trousers, two shoulder-

straps crossing each other at the back of the wearer and having four points of attachment with the trousers in the front, and two points of attachment with the trousers in the rear 5 of the wearer, in combination with a hip-pocket strap attached to one of the shoulder-straps, and means for attaching said hip-pocket strap to the trousers above and in line

with the hip-pocket, substantially as herein shown and described.

In testimony whereof I affix my signature in presence of two witnesses.

ELMER MC GUIRE.
